DESIGN FOR A CIGARETTE LIGHTER

Richard Emil Berthold, New York, N. Y., assignor to Platinum Products Company, Inc., New York, N. Y., a corporation of New York

Application December 3, 1935, Serial No. 59,885

Term of patent 14 years

To all whom it may concern:

Be it known that I, Richard Emil Berthold, a citizen of the United States and a resident of the city of New York, county of Queens, and State of New York, have invented a new, original, and ornamental Design for a Cigarette Lighter, of which the following is a specification, reference being had to the accompanying drawing, forming part thereof.

I claim:

The ornamental design for a cigarette lighter, substantially as shown.

RICHARD EMIL BERTHOLD.
